(57) **CLAIM**

The ornamental design for a tire for automobile, as shown.

DESCRIPTION

FIG. 1 is a perspective view of a tire for automobile in accordance with the new design;

FIG. 2 is a front elevation view of the tire for automobile;
FIG. 3 is a rear elevation view of the tire for automobile;
FIG. 4 is a left elevation side view of the tire for automobile;
FIG. 5 is a right elevation side view of the tire for automobile;

FIG. 6 is a top plan view of the tire for automobile; and,
FIG. 7 is a bottom plan view of the tire for automobile.
The broken lines shown in the drawings are for the purpose
of depicting the claim boundary of the article and form no
part of the claimed design.
